PRODUCTION OF ALKENYLAMINES

George A. Boswell, Hayward, Calif., assignor to Shell Oil Company, New York, N.Y., a corporation of Delaware
No Drawing. Filed Apr. 5, 1961, Ser. No. 160,788
9 Claims. (Cl. 260—583)

This invention relates to a process for converting triallylic amines to diallylic amines or from diallylic amines to monoallylic amines. More particularly, it relates to an improved catalytic process for converting triallylamine to diallylamine.

Triallylamine and diallylamine are both important chemicals of commerce, and are readily prepared by the reaction of an allyl halide, such as allyl chloride, with ammonia. When manufacturing diallylamine from allyl chloride and ammonia, however, undesirably large amounts of triallylamine are formed, and it is generally desirable to convert these to diallylamine. Various physical and chemical methods, e.g., pyrolysis, have been investigated for performing this conversion, but they are generally too expensive or too inefficient to be of commercial interest.

It is an object of the present invention to provide an effective catalytic method for converting triallylic amines to diallylic amines. Another object is the provision of a catalytic process for converting diallylic amines to monoallylic amines. Another object of the invention is the provision of a relatively inexpensive method for converting triallylamine to diallylamine in high yield. Still another object is the provision of a palladium-catalyzed process for converting triallylamine to diallylamine. Provision of a new triolefinic amine is another object of the invention. Other objects will be apparent from the following detailed description of the invention.

These objects are accomplished in the invention by the process which comprises heating an alkenyl amine having $x+1$ (alpha-hydro-beta,gamma-alkenyl) substituents directly connected to the nitrogen atom, x being an integer from 1 to 2, in contact with a hydrogenation catalyst, contacting the resulting product with water, and separating the alkenyl amine having x (alpha-hydro-beta,gamma-alkenyl) substituents from the water. By alpha-hydro-beta,gamma-alkenyl substituent is meant an alkenyl radical of the structure

where R is selected from the group consisting of the hydrogen atom and lower alkyl.

Thus, the process of the invention is one in which a poly(beta,gamma-alkenyl)amine selected from tertiary (beta,gamma-alkenyl)amines and secondary (beta,gamma-alkenyl)amines is catalytically converted to an amine having one more hydrogen atom and one less (beta,gamma-alkenyl) substituent on the nitrogen atom than its precursor. Preferred poly(beta,gamma-alkenyl)amine starting materials are those in which each of the (beta,gamma-alkenyl)substituents on the nitrogen atom has up to 8 carbon atoms.

2

Typical tertiary tri(beta,gamma-alkenyl)amines useful in the process of the invention include tri(2,3-octenyl)amine; tri(2,3-heptenyl)amine; tri(2,3-hexenyl)amine; tri(2,3-pentenyl)amine; and tri(2,3-butenyl)amine. Representative secondary amines are di(2,3-octenyl)amine; di(2,3-hexenyl)amine and di(2,3-butenyl)amine. Unsubstituted allylamines may also be employed. Typical of such amines are triallylamine, tri(methallyl)amine, tri(ethallyl)amine, diallylamine, di(methallyl)amine, di(propallyl)amine, and the like. Preferred amines are, however, the unsubstituted polyallylamines, while the lower alkallylamines, particularly those wherein the alkyl substituent has from 1 to 4 carbon atoms, are also operative.

10 The process of the invention is equally suitable for converting triallylamines to diallylamines, and for converting diallylamines to monoallylamines. As a consequence, while the invention will be described in terms of the preferred embodiment, the preparation of diallylamine, it will be understood that it will be equally effective for the preparation of allylamine, and for the conversion of alkylated allylamines.

15 In the conversion of triallylamine to diallylamine, the triallylamine is heated in contact with a hydrogenation catalyst. The heating may be conducted by passing the triallylamine in the vapor phase over solid catalyst, or by heating the triallylamine in the liquid phase in intimate contact with the catalyst. The most satisfactory catalysts to use, because of the ease with which they may be separated from the reaction system, are the solid hydrogenation catalysts. Such catalysts are preferably selected from metals of groups I, II and IV through VIII of the periodic table, their alloys and derivatives such as their sulfides, oxides and chromites. Examples include silver, 20 copper, iron, manganese, molybdenum, platinum, chromium, cobalt, rhodium, tungsten, mixtures of metals, such as copper-silver mixtures, copper-chromium mixtures, nickel-cobalt mixtures, and their derivatives such as copper oxide, copper chromite, nickel sulfide, silver sulfide, 25 and the like. Particularly preferred catalysts are the members of the group consisting of nickel, copper, cobalt, iron, chromium, silver, palladium and platinum, and their oxides, sulfides and chromites. These catalysts may be employed in a finely divided form and dispersed in 30 and throughout the reaction mixture, or they may be employed in a more massive state, either in essentially the pure state or supported upon or carried by an inert carrier material such as pumice, kieselguhr, diatomaceous earth, clay, alumina, charcoal, carbon or the like, and 35 the reaction mixture contacted therewith as by flowing the mixture over or through a bed of the catalyst or according to other methods known in the art.

40 The amount of the catalyst employed may vary over a considerable range depending upon the type of catalyst employed, the specific amine, the temperatures and pressures, and the like. In general, the amount of the catalyst ranges from about 1% to 35% by weight of the amine but amounts ranging from about 1% to 15% are more preferred. Depending on the several variables involved, 45 it will be found that the catalyst may be recovered and reused for several batches before it becomes necessary to recharge and/or replace it.

50 The reaction may be conducted in any suitable apparatus of the type that is conventionally employed for

hydrogenation processes. Thus, for example, the amine, catalyst and solvent, if desired, are charged to a pressure-resistant vessel equipped with the necessary inlets and outlets, heating means, pressure gauge, thermometer, etc. After the reaction is complete, the reaction product is separated from the by-product and passed to the next step.

The reaction between the triallylamine and the catalyst is conveniently conducted at any temperature between about 50° C. and the decomposition temperature of the amine employed. The optimal temperature for the reaction will, of course, depend both on the nature of the amine and the type and the extent of surface of the catalyst. For example, when triallylamine is employed with palladium catalyst supported on carbon, best results are obtained at temperatures of about 80° C. to 200° C.; while when Raney nickel is used as the catalyst, best yields are obtained at temperatures between about 185° C. to about 250° C. Temperatures up to about 400° C. may, however, be employed.

The catalytic conversion of triallylamine may be conducted at, above or below atmospheric pressure. For example, one convenient mode of effecting the conversion is to reflux the amine at atmospheric pressure in contact with the catalyst, the reflux temperature being about 150° C. Since somewhat better results are obtained at higher temperatures, the use of superatmospheric pressures is preferred. Thus, pressures from about 100 p.s.i.g. to about 5000 p.s.i.g. may be effectively employed, such elevated pressures being achieved by pressuring the system with an inert gas such as nitrogen, helium, argon, carbon dioxide or the like.

When brought into intimate contact with a hydrogenation catalyst under the conditions described, it has been unexpectedly found that instead of hydrogenating or cracking, the triallylamines undergo a conversion to the enamine form. Thus, triallylamine is converted to diallyl methylvinyl amine.

(1)

This behavior is observed for all of the triallylic amines described, the conversion taking place on only one of the three allylically-unsaturated alkenyl substituents of the amine molecule.

The resulting enamines are stable isolatable compounds and may, if desired, be separated from the reaction mixture after the catalytic step and purified in non-aqueous solvents. The enamines derived from the tertiary alpha-hydro-beta,gamma-alkenyl amines will thus be di(alpha-hydro-beta,gamma-alkenyl)mono(gamma - hydro - alpha, beta-alkenyl) amines.

It is convenient, however, to merely separate the catalyst and the allylamine-enamine reaction mixture and bring the latter into contact with water.

Surprisingly, it is observed that when the enamine and the water are brought into intimate admixture, the vinyl substituent of the molecule splits off to afford quantitative formation of diallylamine and propionaldehyde,

(2)

the allylic double bond being unaffected by the water.

In contrast, the equilibrium of the diallylamine inter-

mediate appears to favor the Schiff's base rather than the enamine intermediate

10 The intermediate then reacts with water to afford the monoallylamine and aldehyde:

15 $\text{CH}_2=\text{CH}-\text{CH}_2$ affording the monoallylamine in excellent yield.

The reaction between the enamine and the water may be conducted in liquid phase at any convenient temperature. As a practical matter, the hydrolysis is best accom-

20 plished at any temperature between about 0° C. and 100° C. and at atmospheric pressure, about 20° to about 50° C. being preferred. However, if desired, elevated tempera-

25 tures, up to the decomposition temperature of the product amine, and reduced or elevated pressures, up to about 5000 p.s.i.g., may be employed. Although the hydrolysis requires at least a stoichiometric amount of water, excess of water are most convenient to employ. The recovery of product is inconvenient, however, when more than about 10 moles of water per mole of enamine are used.

30 The desired allylamine product is readily recovered from the reaction system by such conventional methods as steam stripping, fractional distillation, selective extraction, crystallization or any combination thereof. Since

35 the starting polyallylamine is less soluble in water than the product allylamine, this fact may be employed for separation of the amines from the water phase.

The process may be conducted in a batch, semi-batch or continuous manner, with recycle of unconverted starting material if desired. It may be conducted in two steps, the first being the catalytic conversion of the polyallylamine to the intermediate followed by hydrolysis of the intermediate to the product amine. The over-all reaction may thus be written, where $x+y=3$,

50 This procedure lends itself readily to being practiced in a continuous or semi-continuous manner. In such a case, unconverted allylamine could be separated and recycled at the termination of the first step, only the enamine going on to the hydrolysis stage. For example, the catalyst may be separated from the reaction mixture by decantation, filtration, centrifugation or the like, and the allylamine separated from the enamine by extraction, distillation, preferably at low temperature and under

60 reduced pressure or similar methods. The enamine may thus be recovered in pure form for further handling.

65 Equally satisfactory is the conduct of the process of the invention by conducting both the catalytic conversion and the hydrolysis in one operation. Thus, the conversion and hydrolysis may be conducted in one reaction system in situ, without the necessity of separating intermediates or recycling starting allylamines. In such a case the over-all reaction may be written

75 This system is particularly well adapted for being prac-

ticed in a batchwise manner. For example, when triallylamine is refluxed with a catalytic amount of 10% palladium-on-carbon catalyst with water present in the reaction system, the principal products are diallylamine and propionaldehyde.

While the use of solvents in the liquid-phase practice of the process of the invention is not necessary, solvents are sometimes helpful for dilution, for temperature control, and to maintain the catalyst in its dispersed state. Solvents which may be used are preferably inert organic liquids with which the allylamine products and reactants are miscible under the conditions of the process. Typical solvents include such inert liquids as the alkanols, including methanol, ethanol, propanol, isopropanol, the butanols, cyclohexanol, and the like; the ethers, including diethyl ether, methyl ethyl ether, diisopropyl ether, dioxane, tetrahydrofuran and the like; and the esters, such as ethyl acetate, amyl acetate, butyl propionate, methyl formate and the like.

Particularly preferred solvents are those miscible both with the allylamines and with water, since these afford

been converted to a mixture of 40% diallylamine, and about 60% to monoallylamine.

Using the same procedure, tri(methallyl)amine is readily converted to di(methallyl)amine.

Example IV

Anhydrous triallylamine was refluxed over 2.5% wt. of 10% palladium-on-carbon catalyst for approximately 30 minutes. At the end of that time the mixture was cooled and the catalyst filtered therefrom. The filtrate was then diluted with two volumes of water and heated to reflux. At the end of one hour, the volatile components were allowed to steam distill. The amine phase was separated from the distillate, dried over anhydrous sodium sulfate, and analyzed by gas-liquid partition chromatography and infrared spectroscopy. An 85% conversion of triallylamine to diallylamine was obtained.

Examples V-VII

Using the method of Example IV, the following results were obtained using the following reactants and conditions.

Triallyl amine, Amount	Catalyst, Amount	Temp., ° C.	Pressure, p.s.i.g.	Time, min.	Composition of Organic Phase, percent w.

a homogeneous reaction system, especially useful when practicing the invention as a one-step process.

The novel and improved features of the process of the invention are illustrated by the following examples. It should be understood, however, that the examples are merely illustrative and are not to be regarded as limitations on the appended claims, since the basic teachings thereof may be varied at will as will be understood by one skilled in the art. In the examples, the proportions are expressed in parts by weight unless otherwise noted.

Example I

A mixture containing 55 grams of triallylamine, 1.5 grams of carbon-supported palladium catalyst (10% palladium), and 3 grams of water was heated to reflux for 10 minutes. The formation of propionaldehyde was immediately detected by its odor.

At the end of that time, the mixture was cooled and the catalyst separated. The liquid phase was analyzed by gas-liquid partition chromatography. The composition of the reaction mixture was found to be 80% wt. triallylamine, 15% wt. diallylamine, 1% wt. monoallylamine and the remainder a number of unidentified products.

Example II

Diallylamine containing 8% wt. water was allowed to stand at room temperature in admixture with 10% wt. chromium-promoted Raney nickel catalyst. Although no external heat was applied, the mixture became warm. At the end of about thirty minutes, the catalyst was filtered off. Analysis of the filtrate showed it to comprise about 80% wt. diallylamine and about 20% wt. monoallylamine.

Example III

A mixture of 80 grams triallylamine, 50 grams isopropanol solvent, 10 grams water and 2 grams 10% palladium-on-carbon catalyst was heated at 85° C. for 60 minutes. At the end of that time, the mixture was cooled and the catalyst filtered off. The filtrate was analyzed by gas-liquid partition chromatography and showed that about 50% wt. of the triallylamine had

35

45

Example VIII

Triallylamine was heated to 150° C. in contact with 2 grams of 10% palladium-on-carbon catalyst for 30 minutes. At the end of this time, the mixture was cooled and the triallylamine separated from the diallyl 2-methylvinyl amine product by careful fractional distillation. The yield of enamine was about 85%. The product was characterized by its infrared spectrum and by its hydrolysis to diallylamine and propionaldehyde.

Example IX

172 grams of triallylamine and 3.5 grams of 10% palladium-on-carbon catalyst were refluxed together for 30 minutes. To the resulting mixture was added 300 50 ml. of water and the mixture was refluxed for an hour. At the end of this time, the volatile components were allowed to steam distill.

Gas-liquid chromatographic analysis of the organic phase of the distillate showed it to consist of 61 grams of diallylamine, 3 grams of monoallylamine, 18 grams of alpha-methyl-beta-ethylacrolein, 31 grams of unconverted triallylamine, and 1.2 grams of unknown.

I claim as my invention:

1. The process for preparing an alkenylamine selected from the group consisting of a mono(beta,gamma-alkenyl)amine and a di(beta,gamma-alkenyl)amine from the corresponding dialkenylamine and trialkenylamine, respectively, the alkenyl group in each instance containing up to 8 carbon atoms, which comprises heating an alkenylamine selected from the group consisting of said corresponding dialkenylamine and trialkenylamine in contact with a solid metal hydrogenation catalyst at a temperature between about 50° C. and about 400° C. and a pressure up to 5,000 p.s.i.g. to convert one of the alkenyl groups in the alkenylamine to a vinyl group, thereby producing a corresponding beta,gamma-alkenyl vinyl amine, reacting the resulting product with water and converting said alkenyl vinyl amine into the corresponding beta,gamma-alkenylamine and aldehyde, and recovering the alkenylamine.

75

2. The process of claim 1 where the hydrogenation catalyst is palladium.

3. The process for preparing allylamine comprising heating diallylamine in contact with a solid metal hydrogenation catalyst at a temperature between about 50° C. and about 400° C. and a pressure up to about 5,000 p.s.i.g., bringing the resulting product into contact with water, and separating allylamine from the resulting mixture.

4. The process for the conversion of triallylamine to diallylamine comprising heating triallylamine in contact with a solid metal hydrogenation catalyst at a temperature between about 50° C. and about 400° C. and a pressure up to about 5,000 p.s.i.g., bringing the resulting product into contact with water, and recovering the diallylamine therefrom.

5. The process of claim 4 wherein the hydrogenation catalyst is palladium.

6. The process for the conversion of triallylamine to diallylamine comprising heating triallylamine in contact with a solid metal hydrogenation catalyst at a temperature between about 100° C. and about 400° C. and a pressure from atmospheric up to 5,000 p.s.i.g., to form diallyl 2-methylvinyl amine, bringing said diallyl 2-methylvinyl amine into contact with water, and recovering diallylamine from the resulting mixture.

7. The process of claim 6 wherein the hydrogenation catalyst is palladium.

8. The process of claim 6 wherein the hydrogenation catalyst is Raney nickel.

9. Diallyl 2-methylvinyl amine.
